United States Patent Office

Des. 219,495
Patented Dec. 15, 1970

219,495

CIGARETTE-MAKING MACHINE

Robert D. Bessier, Prairie Village, Kans., assignor to
J and O Company, Kansas City, Mo., a partnership of
Ray T. Jenkins and Jason Ott

Filed Aug. 28, 1969, Ser. No. 18,901

Term of patent 14 years

Int. Cl. D27—99

U.S. Cl. D85—7

Fig. 1.

Fig. 2.

Fig. 3.

Fig. 4.

FIG. 1 is a side elevational view of a cigarette-making machine showing my new design;

FIG. 2 is a top plan view;

FIG. 3 is a front perspective view; and

FIG. 4 is a rear elevational view thereof.

I claim:

The ornamental design for a cigarette-making machine, as shown.
